(57) **CLAIM**

The ornamental design for a female connector, as shown and described.

DESCRIPTION

FIG. 1 is a front and right perspective view of a female connector showing the new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a rear and left perspective view thereof;

FIG. 9 is a partial cross-sectional view of the right, front perspective view of the female connector sectioned along line 9-9 in FIG. 6; and,

FIG. 10 is a partial cross-sectional view of the rear, left perspective view of the female connector sectioned along line 10-10 in FIG. 6.

The dot dash broken lines shown define the bounds of the claimed design and form no part thereof.
